SHEET FEEDING MECHANISM

William Pechy, Manasquan, N. J., assignor to
 American Can Company, New York, N. Y., a
 corporation of New Jersey

Application July 22, 1943, Serial No. 495,782

8 Claims. (Cl. 271—32)

The present invention relates to a sheet feeding mechanism for a can making machine or the like and has particular reference to feeding sheets or flat blanks from a magazine at high speeds.

An object of the invention is the provision of a sheet feeding mechanism wherein rotary feeding devices having continuously moving feed fingers are utilized for feeding flat sheets or blanks from a magazine, in rapid succession and in timed relation so that a procession of such blanks moving at high speed may be obtained.

Another object is the provision of such a sheet feeding mechanism wherein movable gauge arms cooperate with the feed fingers in feeding the blanks from the magazine so that each blank as it leaves the magazine while traveling at high speed will be maintained in proper feeding position and will be prevented from shifting in any direction that will result in a jamming of the feeding mechanism.

Another object is the provision of a sheet feeding mechanism of this character wherein stripper dogs release the fed blanks from the gauge arms while traveling at high speed so that the blanks may be readily advanced further in timed order along a predetermined path of travel.

Another object is the provision in such a sheet feeding mechanism of reciprocating feed bars for advancing the stripped off blanks wherein the feed bars are actuated by directly connected rotary, driving means which eliminates lost motion or play between cooperating parts and which insures smooth uniform operation while traveling at high speeds.

Numerous other objects and advantages of the invention will be apparent as it is better understood from the following description, which, taken in connection with the accompanying drawings, discloses a preferred embodiment thereof.

Referring to the drawings:

Figure 1 is a top plan view of a feeding mechanism embodying the instant invention, with parts broken away;

Fig. 2 is a schematic view illustrating the driving parts of the mechanism, with parts broken away;

Fig. 3 is an end view of the mechanism as viewed from the right in Fig. 1, with parts broken away;

Figs. 4 and 5 are longitudinal sections taken substantially along the respective broken lines 4—4 and 5—5 in Fig. 1, with parts broken away;

Figs. 6, 7 and 8 are transverse sections taken

substantially along the respective lines 6—6, 7—7 and 8—8 in Fig. 1, with parts broken away and showing a blank in place in the mechanism;

Fig. 9 is an enlarged perspective view of a portion of the feeding mechanism with a blank in place during the feeding operation, with portions of the device and of the blank broken away; and

Fig. 10 is an enlarged sectional view taken substantially along the line 10—10 in Fig. 5, with parts broken away.

As a preferred embodiment of the instant invention the drawings illustrate a sheet metal blank feeding mechanism for a can making machine of the type, for example, as that disclosed in United States Patent 1,770,041 issued July 8, 1930, to John F. Peters, on Roll bodymaker.

In such a blank feeding mechanism rectangular shaped can body blanks A (Fig. 4) are retained in a horizontally stacked position in a magazine 21 which is located adjacent the entrance end of the machine. The magazine includes a plurality of upright guide bars 22 which confine the blanks to their stacked formation. These bars are secured to side brackets 23 (see also Figs. 1, 3 and 7) and to a cross beam 24 which is fastened to the side brackets. The side brackets are bolted to a pair of spaced upright side frames 25 mounted on a base 26 which parts constitute the main frame of the mechanism and which may be a part of the main frame of the can making machine.

The stack of blanks A within the magazine 21 rests on a pair of spaced and parallel support rails 28 (Figs. 1, 3, 4 and 7) which project into the magazine at the bottom. The outer ends of these rails are secured to a cross bracket 29 which is bolted to a pair of spaced and parallel upright sub-frames 31 disposed between the side frames 25 and fastened to a bed plate 32 bolted to the machine base 26.

The blanks A are fed from the bottom of the magazine 21. When the lowermost blank in the stack is ready to be fed, its central portion is drawn down into a bowed condition between its support rails 28 and is brought into the feed line of the mechanism, as best shown in Fig. 7. This is effected by a suction cup 36 which is disposed under the magazine. The suction cup is secured to one end of an arm 37 (see also Figs. 4 and 6) which is mounted on a pivot pin 38 carried in a pair of spaced bearings 39 of a bracket 41 secured to upright outer side webs 42 of the bed plate 32. The arm is formed with a passageway at one end

which connects with the suction cup and at the other end with a flexible hose 45. The hose leads to any suitable source of vacuum.

The suction cup arm 37 is periodically rocked on its pivot pin 38 in time with the other moving parts of the mechanism to bring the cup 36 into engagement with the lowermost blank in the magazine and to draw this blank down into its bowed condition, as hereinbefore mentioned. This rocking of the cup arm is brought about by a depending lever 47 which is formed on the arm. At its lower end the lever carries a cam roller 48 (see Figs. 4 and 6) which operates against a face cam 49 mounted on a longitudinal cam shaft 51. The cam roller is held in place against the cam by a tension spring 52. One end of the spring is secured to a pin 53 carried in the lever 47 while the other end is fastened in a pin 54 carried in a feed bracket 55 formed on the bed plate 32.

The cam shaft 51 is preferably journaled in three bearings, an intermediate bearing 58 (see Fig. 5) and two end bearings 59. The intermediate bearing is formed integrally with the bed plate 42 and the two end bearings are in brackets which are bolted to the bed plate.

The cam shaft 51 is continuously rotated by a bevel gear 61 (see also Fig. 2) which is mounted on the inner end of the shaft. This gear meshes with and is driven by a bevel gear 62 carried on a main drive shaft 63 which extends transversely of the mechanism. The drive shaft is journaled in a pair of spaced bearings 64, 65. Bearing 64 is formed on one of the upright webs 42 of the bed plate 32 while bearing 65 is formed on one of the side frames 25. The shaft is driven in any suitable manner.

While a blank A is held temporarily in its bowed-down condition it is pushed out or fed from the magazine 21 in a lateral direction. This feeding of the blank is effected by a rotary feeding device 71 (Figs. 1 and 4) which is located under the magazine. The rotary feeding device includes a rotatable spider wheel 72 (see also Fig. 9) having an enlarged hub from which pairs of spaced and parallel spider arms 74 radiate. There are four pairs of these spider arms shown in the drawings.

The spider wheel 72 is secured, by long bolts 75 (see also Fig. 10) which extend through the wheel hub, to a flange 76 formed as an integral part of a short wheel shaft 77 journaled in a bearing 78 formed in one of the upright sub-frames 31. The shaft and the spider wheel 72 carried thereon are continuously rotated by a spur gear 79 which is mounted on the outer end of the shaft.

The gear 79 meshes with and is driven by a piston 81 (Figs. 2, 3 and 5) mounted on a short jack shaft 82 journaled at its ends in a bearing formed in the adjacent subframe 31 and in a bearing bracket 83 bolted to the bed plate 32. The jack shaft is rotated by a bevel gear 84 which is mounted thereon and which meshes with and is driven by a bevel pinion 85 carried on the cam shaft 51. In this manner the spider wheel 72 is rotated in timed relation with the cam shaft 51 and in time with the suction cup 36 which is actuated by the cam shaft.

The spider wheel 72 carries a plurality of hingeable feed finger units 90 each of which includes a pair of transversely spaced feed fingers 91 formed at their outer ends with hook sections 92. Each pair of fingers is formed on a carrier block 93 (see Fig. 9) having two spaced and parallel lugs 94 which carry a pivot pin 95. Between the lugs, the pivot pin extends through one end of a rocker link 96. The opposite end of the link is mounted

on a rocker pin 97 carried in bearings 98 formed on the outer ends of the spider wheel arms 74.

The feed finger units 90 travel round through a circular path of travel with the rotating spider wheel 72 and also are movable relative to the wheel in a rocking motion which motion is brought about by cam action. For this latter purpose one end of the pivot pin 95 in the carrier block 93 extends beyond its lug 94 and carries a cam roller 101 which operates in a cam groove 102 of a stationary face cam 103 secured to one of the upright sub-frames 31 (see Fig. 10). The carrier block also supports on the side opposite to the cam roller 101, another cam roller 105 (Fig. 9) which is mounted on a pin 106 secured in the side of the block. Roller 105 operates in a cam groove 107 (Fig. 10) formed in a stationary face cam 108 secured to the adjacent subframe 31.

The shapes of the cam grooves 102, 107 in the stationary cams 103, 108 are such that as the cam rollers 101, 105 traverse the grooves with the rotation of the spider wheel 72, the feed fingers 91 come up behind the bowed-down blank A in the bottom of the magazine 21 and travel for a moment along a straight line path of travel toward the blank, as shown in Fig. 4. During this travel, the fingers engage behind the blank (as best shown in Figs. 5 and 9). The suction cup 36 at that time releases its hold on the blank and the fingers push it edgewise from under the stack of blanks in the magazine. Release of the cup from the blank is effected in the usual manner by way of valves (not shown) in the suction line which are operated in time with the other moving parts of the mechanism.

While the blank is being removed from the magazine its forward or inner edge is supported by a pair of gauge arms 111 (Fig. 5) having blank supporting lugs 112 which maintain the blank in proper feeding position and which prevent inadvertent shifting of the blank in a direction that might result in a jamming of the feeding mechanism. There are two of these gauge arms 111 located in front of the magazine 21 and disposed in spaced relation adjacent the ends of the magazine (see Figs. 1 and 7).

These gauge arms are mounted on a transverse rocker shaft 115 which is carried at its ends in a bearing bracket 116 bolted directly to one of the side frames 25 and in a sub-bearing bracket 117 secured to a bearing bracket 118 fastened to the opposite side frame 25.

The rocker shaft 115 is actuated by cam action in time with the other moving parts of the mechanism. Its rocking movement is brought about by a pair of spaced cam rollers 121 (see also Fig. 2) which are carried on rotor pins 122 (see Fig. 4) secured in a web section 123 of one of the gauge arms 111. The cam rollers straddle and operate against opposite cam faces 125 of a continuously rotating thread cam 126 (Fig. 2). The thread cam is mounted on the outer end of an auxiliary cam shaft 127 which is journaled at its ends in the bearing bracket 118 and in a sub-bearing bracket 128 (Figs. 1, 4 and 8) bolted to a bearing bracket 129 secured to the same side frame 25 to which the bracket 118 is fastened.

The auxiliary cam shaft 127 is rotated by a spur gear 132 (Figs. 1, 4 and 8) which is mounted on the shaft and which meshes with a gear 133 mounted on a short sprocket shaft 134. The sprocket shaft is journaled in the bearing bracket 129 and in a bracket 135 bolted to the side frame 25 adjacent the bracket 129. This sprocket shaft 135 is rotated by an endless chain 138 (see also Fig.

6) which operates over a driven sprocket 139 mounted on the sprocket shaft 134 and over a driving sprocket 141 mounted on a short auxiliary drive shaft 142.

The auxiliary drive shaft 142 is journaled in a bearing bracket 143 (Figs. 2 and 6) bolted to the side of one of the side frames 25. This drive shaft carries a bevel gear 145 which meshes with and is driven by a bevel gear 146 carried on the main drive shaft 63. It is through this connection with the main drive shaft that the gauge arms 111 are actuated in time with the other moving parts of the mechanism.

The gauge arms 111 have no normal stationary position but move toward and away from the magazine 21 in time with the removal of the blanks. As a blank is being drawn down into a bowed condition as hereinbefore explained, the gauge arms move in toward the magazine and engage under the forward edge of the blank at places adjacent its end as shown in Fig. 5. The arms are in this position when the feeding fingers 91 come into engagement with the rear edge of the blank as shown in this same figure. After engagement of the feed fingers, the fingers and the gauge arms move forward in synchronism and in the same direction the while supporting the blank, the fingers pressing the blank against the gauge to hold the blank in square while it is removed horizontally from the magazine and fed forward. It is this hold on the blanks during removal from the magazine that insures satisfactory results at high speed operation.

When a blank is fully removed from the magazine 21 it is brought under the control of a pair of movable stripper dogs 151 (Figs. 4 and 5) which clamp down on the moving blank and thus hold it against the feeding fingers 91 while the gauge arms 111 move away to release the blank. There are two of these stripper dogs 151 located on opposite sides of the center of the path of travel of the blank and they may be disposed at the ends of and secured to a long hub 152 mounted on a transverse, stripper rock shaft 153 (see also Figs. 1, 2 and 6).

The stripper rock shaft 153 is carried at its ends in a pair of spaced bearing brackets 155 bolted to the side frames 25. The shaft is periodically rocked to swing the stripper dogs 151 through a down or stripping stroke and thence through a return stroke, by an actuating lever 156 which is mounted on one end of the shaft. The lever carries a cam roller 157 that operates against a cam face 158 of a continuously rotating cam 159 mounted on the auxiliary cam shaft 127. The roller is held against the cam face by a tension spring 161. One end of the spring is fastened to the lever 156 while its opposite end is hooked into a vertical pin 162 (Fig. 4) secured in a bracket 163 bolted to the side frame 25.

The normal position of the stripper dogs 151 is shown in Fig. 5. As an advancing blank A comes into position under the raised dogs, they move down onto the blank as shown in Fig. 4. It is during this movement of the stripper dogs that the gauge arms 111 move back out of the way of the blank to release it for further advancement.

The released blank, still moving forward under control of the feeding fingers 91 is received on a plurality of horizontal support bars which include a pair of spaced and parallel inner support rails 171 (Figs. 1 and 6) and a pair of similarly arranged outer guide rails 172. These rails extend from the magazine 21 to the opposite end of the

feeding mechanism and guide the blanks along a straight line path of travel through the mechanism.

The outer guide rails 172 are bolted to the tops of the two side frames 25. The inner support rails 171 are secured to a pair of slideway gibs 173 (Fig. 8) which are mounted on the web sections 42 of the feed bracket 55. These inner rails support the blanks intermediate their ends.

10 The slideway gibs 173 confine a horizontal and reciprocable slide 175 which carries on its top face a pair of spaced and parallel feed bars 176 having depressible feed dogs 177 secured thereto at spaced intervals along their lengths. These feed bars pick up an advanced blank from the feeding fingers 91 and further advance it along the support rails 171 and along the guide rails 172 in a step-by-step or intermittent manner.

The slide 175 and the feed bars 176 carried thereon, are reciprocated through a forward or feeding stroke and thence through a return stroke in time with the other moving parts of the mechanism, by a cam roller 181 (Figs. 4, 5 and 8) which operates in a straight transverse groove 182 formed in a boss 183 which depends from the slide. The cam roller is carried on a continuously rotating horizontal feed disc 185 which is mounted on the upper end of a vertical disc shaft 186 journaled in a pair of spaced bearings 187 formed in the feed bracket 55.

25 The disc shaft 186 is rotated by way of a bevel gear 191 secured to the lower end of the shaft which meshes with and is driven by a bevel gear 192 mounted on one end of a short gear shaft 193 (see also Fig. 2). The gear shaft is journaled in a long bearing 194 formed in the feed bracket 55. This shaft carries a spur gear 195 which meshes with and is driven by a gear 196 mounted on the cam shaft 51 (see also Fig. 6).

30 Hence while a pair of feeding fingers 91, in traveling around with the spider wheel 72, removes a bowed-down blank A from the magazine 21, the feed disc 185 shifts the slide 175 and its feed bars 176 back through a return stroke and thus brings the first set of feed dogs 177 into position to receive the blank when it is fully removed from the magazine and when stripped from the gauge arms 111.

35 As the blank is received on the support rails 171 and in the guide rails 172, the slide 175 and its feed bars 176 make a forward stroke. On this forward stroke the feed dogs 177 engage behind the rear edge of the blank and take the blank away from the feeding fingers 91 and advance it one step along its path of travel between the guide rails 172.

40 As soon as the blank has been picked up by the feed dogs 177, the feeding fingers 91 through the action of the cams 103, 108, fall back slightly to clear the blank and then pass around with the spider wheel into position to remove another blank from the magazine. During subsequent strokes of the feed bars 176 the partially advanced blank is stepped along through a plurality of idle stations toward the discharge end of the mechanism.

45 During this advancement, the blank is held after each step against return with the feed bars 176, by stationary depressible hold-back dogs 197 (Figs. 1, 6 and 8). Dogs 197 are carried in a pair of stationary hold-back bars 198 disposed parallel with and adjacent to the feed bars. These hold-back bars are formed as a single unit with end tie bars 199. At the discharge end of the mechanism the end tie bar

is secured to a cross rail 201. The ends of the cross rail are bolted to the side webs 42 of the feed bracket 55. The stationary hold-back bars 198 intermediate the opposed end tie bars 199 rest on top of the slide 175.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

I claim:

1. In a high speed sheet feeding mechanism for feeding sheet blanks from a stack of blanks, the combination of a magazine for retaining the stack of blanks, separating means disposed adjacent said magazine for flexing and partially separating an outer blank from the stack in the magazine, rotatable feeding means disposed adjacent said magazine, a feeding finger independently movably mounted on said rotatable feeding means, said finger being also movable with said feeding means through a curved path of travel for engaging behind the partially separated blank and to remove it from the magazine at high speed, and means disposed adjacent said feeding means for controlling the independent movement of said feeding finger as it travels along said curved path of travel.

2. In a high speed sheet feeding mechanism for feeding sheet blanks from a stack of such blanks, the combination of a magazine for retaining the stack of blanks, separating means adjacent said magazine for flexing and partially separating an outer blank from the stack in the magazine, rotatable feeding means disposed adjacent said magazine, a feeding finger hingeably mounted on said rotatable feeding means and movable through a curved path of travel with said feeding means for engaging behind the partially separated blank and for removing it from the magazine at high speed, and cam means disposed adjacent said feeding means for controlling the movement of said feeding finger as it travels along said curved path of travel.

3. In a high speed sheet feeding mechanism for feeding sheet blanks from a stack of such blanks, the combination of a magazine for retaining the stack of blanks, a suction cup movable toward and away from said magazine for flexing and partially separating from the magazine successive outer blanks in the stack, a rotatable spider wheel disposed adjacent said magazine and operating in time with the movement of said suction cup, a plurality of feeding fingers hingeably mounted on said spider wheel and movable through a curved path of travel, and cam means disposed adjacent said spider wheel for controlling the movement of said feeding fingers as they travel along said curved path of travel, said cam means being formed to guide said feeding fingers along a straight line adjacent said flexed blanks for engaging behind successive blanks and for pushing them edgewise, individually and successively from said magazine at high speed.

4. In a high speed sheet feeding mechanism for feeding sheet blanks from a stack of such blanks, the combination of a magazine for retaining the stack of blanks, separating means adjacent said magazine for flexing and partially separating from the magazine an outer blank

in the stack, rotatable feeding means disposed adjacent said magazine, a feeding finger carried on said rotatable feeding means and movable through a curved path of travel for engaging behind the partially separated blank and for removing it from the magazine at high speed, and a gauge arm movable toward and away from said magazine and engageable under an edge of the flexed blank opposite said feeding finger while said finger is removing the blank from the magazine for maintaining the blank in proper feeding position so that jamming of the blank in the mechanism will be prevented.

5. In a high speed sheet feeding mechanism for feeding sheet blanks from a stack of such blanks, the combination of a magazine for retaining the stack of blanks, separating means adjacent said magazine for flexing and partially separating from the magazine an outer blank in the stack, rotatable feeding means disposed adjacent said magazine, feeding fingers carried on said rotatable feeding means and movable through a curved path of travel with said feeding means for engaging behind the partially separated blank and for removing it from the magazine at high speed, a plurality of gauge arms movable toward and away from said magazine and engageable under an edge of the flexed blank opposite said feeding fingers while said fingers are removing the blank from said magazine for maintaining the blank in a proper feeding position and to prevent jamming of the blank in the mechanism, and actuating means operating in synchronism with said feeding means for shifting said gauge arms into blank supporting position and for releasing said gauge arms from the blank in time with said feeding means.

6. In a high speed sheet feeding mechanism for feeding sheet blanks from a stack of such blanks, the combination of a magazine for retaining the stack of blanks, separating means adjacent said magazine for flexing and partially separating from the magazine an outer blank in the stack, rotatable feeding means disposed adjacent said magazine, a feeding finger carried on said rotatable feeding means and movable through a curved path of travel with said feeding means for engaging behind the partially separated blank and for removing it from the magazine at high speed, a gauge arm movable toward and away from said magazine and engageable under an edge of the flexed blank opposite said feeding finger while said finger is removing the blank from the magazine for maintaining the blank in proper feeding position, and stripper means engageable with a blank being removed from said magazine for releasing the blank from said gauge arm.

7. In a mechanism for feeding at high speed sheet material from a stack of such sheet material, the combination of a magazine for retaining the sheet material in a stack, separating means adjacent said magazine for flexing and partially separating from the magazine the outermost of the sheet material in the stack, rotatable feeding means disposed adjacent said magazine, a feeding finger carried on said rotatable feeding means and movable through a curved path of travel with said feeding means for engaging behind the partially separated sheet material and for removing the same from the magazine, a gauge arm movable toward and away from said magazine and engageable under an edge of the flexed sheet material opposite said feeding finger while said finger is removing the same

from the magazine for maintaining proper feeding position and for preventing jamming of the material in the mechanism, a plurality of stripper dogs pivotally mounted adjacent said magazine and movable into engagement with the sheet material being removed for releasing the same from said gauge arm while maintaining it in engagement with said feeding finger for further advancement by the finger, and actuating means for operating said stripper dogs in time with said gauge arm.

8. In a mechanism for feeding at high speed sheet material blanks from a stack of such blanks, the combination of a magazine for retaining the stack of blanks, separating means adjacent said magazine for flexing and partially separating from the magazine the lowermost blank in the stack, rotatable feeding means disposed adjacent said magazine, a feeding finger carried on said

5 rotatable feeding means and movable through a curved path of travel for engaging behind the partially separated blank and for removing it from the magazine at high speed, a reciprocating feed bar disposed adjacent said magazine and having a feed dog thereon for receiving a removed blank from said feeding finger and for advancing the blank further, and a direct connection rotatory feeding device for reciprocating said feed bar, said feeding device including a rotatable disc operable in time with said feeding means, a cam roller mounted on said disc and operable in a transverse, straight slot formed in a boss connected with said feed bar for eliminating lost motion in said feeding device and for insuring smooth uniform operation while traveling at high speeds.

10 15 WILLIAM PECHY.
